UNITED STATES PATENT OFFICE.

WILLIAM R. PARK, OF TAUNTON, AND BELVIN T. WILLISTON, OF SOMERVILLE, MASSACHUSETTS, ASSIGNORS TO THE HANCOCK INSPIRATOR COMPANY, OF BOSTON, MASSACHUSETTS.

COMPOSITE INJECTOR.

SPECIFICATION forming part of Letters Patent No. 621,367, dated March 21, 1899.

Application filed January 24, 1899. Serial No. 703,302. (Model.)

To all whom it may concern:

Be it known that we, WILLIAM R. PARK, a resident of Taunton, county of Bristol, and BELVIN T. WILLISTON, a resident of Somerville, county of Middlesex, State of Massachusetts, citizens of the United States of America, have invented certain new and useful Improvements in Composite Injectors, of which the following is a specification.

10 This invention is an improvement in the mechanism relating to composite injectors wherein two independent valve-actuating levers are employed to control the operation of the several lifting and forcing instruments. 15 It is a simple matter to mount the lever and the lever-frame, the latter consisting of pivoted links in the case of a single injector or inspirator—such as, for instance, the machine shown in United States Letters Patent No. 20 492,944, issued to us on March 7, 1893; but in the case of a composite injector—such as, for instance, that shown in United States Letters Patent No. 609,163, issued to us August 16, 1898—a different condition arises. When the 25 mode of mounting the valve-lever on a single injector or inspirator is transferred by mere duplication to the composite injector, the several sets of valve-levers and link-frames have to be spread apart, so as not to interfere with 30 each other, and this arrangement necessitates an abnormal proportioning of some parts of the composite-injector casing. For instance, in the injector of Patent No. 609,163 the tubes of the smaller set are spread wide apart, the 35 steam-valve being quite remote from the lifter. (See Fig. 5, Patent No. 609,163.) While this distortion from the normal arrangement does not apparently interfere with the working of the machine, yet the necessities 40 of the situation develop an injector-casing which is unusually deep in the body and which contains far more than a desirable weight of metal. This consideration is important, because this class of injectors is designed especially for locomotive-engines. 45 Any excess of weight in the injector adds unduly to the strains put upon the couplings and supports and exaggerates the effects due to vibration when the engine is in motion.

50 By the invention herein described the sev-

eral valve-levers are mounted at the same level and at the same time are reconciled to each other's movements, no valve-handle interfering with the independent operation of another. Furthermore, the same symmetrical 55 and firm support is given to each valve-operating handle as is furnished by the double-bar-link frame shown in either of the two above-named patents.

Another feature of this invention lies in the 60 fact that the entire articulated supporting and operating mechanism of the several sets of valve handles or levers is securely held in operative position by a single master-bolt. Nuts, keys, screws, &c., are dispensed with, 65 and the whole contrivance may be assembled or taken down in a moment. Only a single nut has to be manipulated. This arrangement greatly adds to the strength and simplicity of the device and renders it susceptible 70 of quick repair.

In the drawings hereto annexed, wherein like letters are uniformly employed to designate like parts, Figure 1 shows the operating end of a composite injector; Fig. 2, a plan view of the link-frame and valve-handles, 75 and Fig. 3 the valve-lever frame disconnected and the parts distributed.

On the injector-casing I are cast studs or trunnions T, which are turned to cylindrical form, the two cylinders having one common axis. On the trunnions T the main or primary lever-frame is mounted. This primary frame consists of side bars B B', in the ends of which bearings E E' are formed, the said bearings being made to fit over the trunnions T. From the inner side of the bar B projects a bearing-stud B². The bar B is perforated at H and G, the hole H passing axially through the bearing-stud B². The bar B' carries a 85 sleeve-shaped extension B², opposite the end of which is the hole H'. In the end of bar B' is the hole G'. The holes E, H, and G of the bar B are spaced between centers exactly the same as holes E', H', and G' of bar B', so that when the two side bars are mounted on the trunnions T the holes come exactly opposite each other, H registering with H' and G with G'. The valve-operating lever L is 95 formed of one casting, which carries as an in- 100

tegral part the lateral arm P. The arm P and the opposite fork of lever L are finished off with studs S S', which are turned to fit the holes of G G' bars B B'.

5 The secondary lever-frame consists of two side bars b b', on which are sleeves t t'. Holes g g' in the ends of the side bars b b' are formed so as to admit the studs s s', which are integral parts of the casting which forms the valve-
10 lever l.

The bore of the sleeves t t' corresponds with the external diameter of the bearing-stud B³, which has an internal bore adapted to receive the master-bolt M.

15 The valve-stems are shown at V and v. The lever-frame is assembled as follows: Connect each valve-lever with its valve-stem. Insert stud S in hole G and place the bearing E on trunnions T. Place the studs s s' into
20 holes g g', respectively, and slip the two sleeves t t' over the bearing-stud B³, and then place bearing E' on its trunnion, at the same time slipping stud S' into hole G'. Then slip the master-bolt M through hole H, sleeve B²,
25 and hole H' and bring up the bolt-head N on bar B by screwing nut O on the threaded end of the master-bolt M. The bolt M holds the whole structure firmly together. The stud-and-socket connections are simple and strong
30 and easy to assemble or disconnect. Each valve-lever has its own independent mounting and is independent of the other. The two valve-stems are on the same level. The entire composite injector can be compactly
35 and economically proportioned, and a burden of useless metal is removed.

What we claim, and desire to secure by Letters Patent, is—

1. In a lever-frame for composite injectors,

the combination of a primary lever-frame pivoted on the injector-casing, a secondary lever-frame pivoted on the primary frame, levers pivoted on the primary and secondary lever-frames, respectively, the said levers being provided each with its valve-stem and 40 connections, substantially as described.

2. In a lever-frame for composite injectors, the combination of a primary lever-frame hung on trunnions to the injector-casing, a secondary lever-frame pivoted on the primary frame, levers pivoted on the primary and secondary lever-frames, respectively, and provided each with its valve-stem and 50 connections, and master-bolt, extending from side to side of the primary lever-frame, the 55 said bolt confining the articulated parts of the primary and secondary lever-frames in operative relationship, substantially as described.

3. In a lever-frame for composite injectors, 60 the combination of a primary lever-frame consisting of two side bars pivoted to the injector-casing, a valve-handle pivoted on a rocking shaft between said side bars, the rocking shaft and side bars being articulated 65 by stud-and-socket connections, a secondary lever-frame pivoted upon a master-bolt, the said bolt passing from side to side of the primary lever-frame and holding the side bars thereof in operative relationship with the articulated parts, substantially as described. 70

Signed by us, at Boston, this 2d day of January, A. D. 1899.

WILLIAM R. PARK.
BELVIN T. WILLISTON.
